UNITED STATES PATENT OFFICE.

ALLEN D. MOORE, OF MONTPELIER, VERMONT.

GOVERNOR.

SPECIFICATION forming part of Letters Patent No. 530,704, dated December 11, 1894.

Application filed August 4, 1892. Serial No. 442,187. (No model.)

To all whom it may concern:

Be it known that I, ALLEN D. MOORE, a citizen of the United States, residing at Montpelier, in the county of Washington and State 5 of Vermont, have invented a new and useful Improvement in a Governor, of which the following is a specification, accompanied by drawings representing a governor embodying my invention and forming a part of this specification.

The governor shown in the accompanying drawings is represented as applied to the valves of a water-motor, but it can be used in connection with movable valves of various 15 classes, whether such valves are used to control the flow of water, or steam, or for other purposes.

In the accompanying drawings:—Figure 1 is a top view of my improved governor applied 20 to a pair of valves by which water is admitted to the bucket wheel of a water-motor, the inclosing shell, or case, of the water-motor and the belt pulley upon the water-motor shaft being shown in central sectional view, in order 25 to disclose more clearly the operating parts. Fig. 2 is a top view of that portion of the operating part of the mechanism which is intermediate between the rod connecting the two valves and a sliding collar, actuated by the 30 centrifugal force of the weights carried upon blade springs attached to the rotating pulley. Fig. 3 is a side view of the governor, the pulley E having been turned one quarter of a revolution from its position as shown in Fig. 35 1 and represented in central sectional view upon the same plane as the section shown in Fig. 1. Fig. 4 shows an end view of the sliding collar and the operative mechanism intermediate between the sliding collar and the 40 rod connecting the valve, the shaft being shown in section, and Fig. 5 represents a perspective view of the yoke G.

Similar letters refer to similar parts in the different figures.

Referring to the accompanying drawings, A denotes the shell, or case of the water-motor, B the bucket wheel inclosed therein and attached to the shaft C, journaled in the bearings C' and C'', which are supported by the 50 frame-work of the machine.

The valves to which my improved governor

is represented as applied, consist of the rocking cylinders D, D, inclosed in the tubes D', D', to which water under pressure is admitted and which form the water chambers. The 5 valve cylinders D are provided with openings D², D², in their sides and these openings are brought coincident with the port holes D³, D³, in the sides of the tubes D', in order to open the valves and admit water to the bucket 60 wheel B.

Valve stems D⁴, D⁴ are carried outside the inclosing shell, or case of the motor, through stuffing boxes D⁵, D⁵ and to the ends of the valve stems are attached the radial arms D⁶, 65 which are connected by the connecting rod D⁷.

The above described arrangement of valves forms no part of my present invention, those features of the valve mechanism shown in the accompanying drawings which are novel, having 70 been made the subject of a separate application for Letters Patent.

Attached to the shaft C is a belt pulley E having a rim E', a hub E² and a web E³. Sliding upon the hub E², but connected therewith 75 by a spline E⁴ is a ring or collar F.

The web E³ is provided with holes or openings E⁵ to allow the radial movement of blade springs F² and F³, which are attached, respectively, to the sliding collar F and to the inner 80 surface of the rim E'.

The blade springs F² and F³ are arranged in pairs with their free ends united and to their united ends are loosely attached the weighted washers F⁴, F⁴ by bolts F⁵. 85

The sliding ring or collar F is provided with an annular groove, in which is held a strap F' made in halves similar to the strap of an "eccentric" and from each half project the studs F⁶, which pass through holes in the 90 arms G', G' of the yoke G.

The yoke G is provided with gudgeons G² which are held in brackets G³ attached, in the mechanism shown, to the shell or case A, but which can be held by any supporting frame-work. 95

From the body of the yoke G and at right angles to the arms G', G', is an arm G⁴ extending beneath the valve connecting rod D⁷ and carrying a stud G⁵ entering a hole in the 100 rod. A spring G⁶ is attached at one end to the arm G⁴ and with its opposite end connected

to a screw threaded bolt G⁷ held in a bracket G⁸ attached to the shell A and provided with a thumb nut G⁹.

The weighted washers F⁴ are carried from 5 the position shown in Fig. 3 to the position shown by the broken lines H in Fig. 3 by the centrifugal force produced by the rotation of the shaft C and pulley E, causing the longer blade springs F³ to straighten, while the 10 shorter blade springs F² serve as connecting links to draw the sliding ring, or collar along the hub E² of the pulley E and into the position indicated by the broken line H', Fig. 3 and this sliding movement of the collar F 15 causes the yoke G to be rocked upon the gudgeons G², imparting an angular motion to the arm G⁴ and a longitudinal movement of the valve connecting rod D⁷ and producing the simultaneous rocking motion of the valve cylinders D, D, tending to close the ports D³, D⁸. 20

The rocking motion of the yoke G upon its gudgeons G² as already described, is effected against the tension of the spring G⁶, which resists the centrifugal force applied to carry 25 the weighted disks F⁴, F⁴, outward. Therefore it will be obvious that the speed required to produce a given radial movement of the weighted disks F⁴ can be varied by increasing or decreasing the tension of the spring G⁶, which can readily be accomplished by 30 means of the screw threaded bolt G⁷ and thumb nut G⁹, allowing the action of the valve cylinders D, D, to be controlled and the ports D³, D⁸, to be closed by a pre-determined rate 35 of speed of the shaft C.

The operative mechanism constituting the governor proper can readily be applied to a single valve as well as to two valves intended to work simultaneously, or to a sliding instead 40 of an oscillating valve.

I am aware that governors actuated by the centrifugal force applied to weights carried by revolving pulleys and acting against the tension of a spring are not new, and I do not 45 herein claim such broadly.

Instead of the belt pulley E, radial arms can project from the shaft C, to which the springs F³ can be attached and the sliding ring or

collar F can slide directly on the shaft C, as well as upon the hub of the pulley as shown, 50 the operation being the same in either case and I do not therefore confine myself to the employment of a pulley for the purpose of carrying the springs F³.

What I claim as my invention, and desire 55 to secure by Letters Patent, is—

1. The combination of a revolving shaft C and a pulley carried by said shaft, of a collar capable of sliding on said shaft, but having a spline connection therewith, a spring F³ attached at one end to said sliding collar and a weight attached to its opposite end, said spring being arranged with its weighted end nearer the axis of said revolving shaft than its attached end, a blade spring F² connecting 60 the weighted end of said spring F³ with said pulley, whereby the centrifugal force applied to the weighted end of said spring by the rotation of said shaft will carry said weighted end away from the axis of the shaft and slide 70 said collar, a pivoted yoke G engaging said sliding collar, an arm G⁴ extending from said yoke, a rocking valve having a radial arm D⁶ and a link connecting said radial arm D⁶ with said arm G⁴, substantially as described. 75

2. The combination with a valve and a revolving shaft, of a ring or collar rotated with said shaft; but capable of sliding thereon, a pulley attached to said shaft and inclosing said sliding ring, a blade spring having one 80 end attached to said ring, a weight attached to the opposite end of said spring, said spring being curved so as to bring its weighted end nearest the axis of said shaft and a blade spring connecting the free end of said weighted spring with said pulley, so that when said curved spring is straightened, it will cause 85 said sliding ring to move lengthwise said shaft and a pivoted yoke engaging said sliding ring, said yoke being operatively connected with 90 said valve, substantially as described.

Dated the 28th day of July, 1892.

ALLEN D. MOORE.
